PLASTIC CUP OR THE LIKE

John A. Noel, 4238 N. 28th St.,
Phoenix, Ariz. 85015

Filed Apr. 26, 1967, Ser. No. 6,871

Term of patent 14 years

U.S. Cl. D9—242
Int. Cl. D9—04

FIG. 1 is a perspective view of the plastic cup in inverted position showing my new design;

FIG. 2 is a fragmentary plan view of the cup shown in FIG. 1 disclosing the bottom rim of the inverted cup;

FIG. 3 is a fragmentary side view of FIG. 1; and

FIG. 4 is an enlarged cross-section taken on line 4—4 of FIG. 2.

The dominating features of the invention are shown in solid lines in the figures, and particularly include the lug pattern on the inside rim of the cup.

I claim:

The ornamental design for a plastic cup or the like, substantially as shown and described.
